United States Patent Office

Des. 196,366
Patented Sept. 24, 1963

196,366

ENCASED STATIC SWITCHING UNIT

Robert C. Mierendorf and Richard C. Rothweiler, Wauwatoska, Wis., assignors to Square D Company, Park Ridge, Ill., a corporation of Michigan

Filed Nov. 18, 1959, Ser. No. 58,386

Term of patent 14 years

(Cl. D26—5)

FIG. 1

FIG. 2

FIG. 3

FIG. 4

FIG. 1 is a perspective view of an encased static switching unit showing our new design.

FIG. 2 is a top plan view thereof.

FIG. 3 is a side elevational view, the opposite side being substantially a mirror image thereof; and

FIG. 4 is an end elevational view, the opposite end being substantially a mirror image thereof.

We claim:

The ornamental design for an encased static switching unit, substantially as shown and described.
